Specification for Design.

Patented Jan. 3, 1911.

Application filed November 7, 1910. Serial No. 591,209. Term of patent $3\frac{1}{2}$ years.

To all whom it may concern:

Be it known that I, ADOLPH PETZOLD, a citizen of the United States, residing in the city of Philadelphia, State of Pennsylvania, have invented a certain new, original, and ornamental Design for Rugs, of which the following is a specification, reference being had to the accompanying drawing, forming part thereof.

The figure is a plan view of a half-section of a Smyrna rug, the other half-section being identical therewith, showing my new design.

I claim:—

The ornamental design for a rug, as shown.

ADOLPH PETZOLD.
